UNITED STATES PATENT OFFICE.

REUBEN CLARKE, OF TORONTO, ASSIGNOR OF ONE-HALF TO ANDREW FORESTER BARRON, OF SARNIA, ONTARIO, CANADA.

DOOR-HANGER.

SPECIFICATION forming part of Letters Patent No. 395,693, dated January 8, 1889.

Application filed August 6, 1888. Serial No. 282,041. (No model.)

To all whom it may concern:

Be it known that I, REUBEN CLARKE, of the city of Toronto, in the county of York, in the Province of Ontario, Canada, inventor, have 5 invented a certain new and Improved Support for Sliding Doors, of which the following is a specification.

The object of the invention is to design a simple and easily-applied rolling support by 10 which a sliding door may be evenly carried and be kept perfectly plumb without the necessity of laying a track across the opening between the jambs of the door; and it consists in the peculiar combinations and the novel 15 construction and arrangement of parts, all as more fully hereinafter described and claimed.

Figure 1 is an elevation of a pair of doors and doorway partially in section to expose the construction of my device. Fig. 2 is a perspective detail of the upper roller and its bracket. Fig. 3 is a detail of the bottom rail of the door, showing a substitute for the lower 20 roller. Fig. 4 is a detail of the upper rail of the door, showing a substitute for the upper roller.

A is the door, and B a roller journaled in a suitable bracket secured to the lower inner corner of the door A. This roller rests upon a track, C, which, when the door slides into a 30 bracket or recess, as indicated in Fig. 1, is slipped into the said recess, as shown, and is very simply fixed in position in the following manner—*i. e.*, a cross-bar, a, made just long enough to extend across the pocket or recess, 35 is fixed to the inner end of the track C, so that when the said track is slipped into the pocket its inner end will be held by the cross-bar a exactly in the center of the said pocket. A similar cross-bar, b, is fixed to the outer end 40 of the track C in such a position that it may

be readily screwed onto the floor. Separate pieces on each side of the track C may be substituted for the cross-bar b.

D is a bracket secured to the upper outer corner of the door A, and has jaws d formed on it, between which an adjusting bearing-box, e, is fitted. A pair of rollers, E, is journaled in the bearing e, and rests upon a double track, F, located above the door, and extending across the doorway. A shank, f, is connected to the 45 bearing e and extends through the bracket D and a wedge-shaped block, G. A pin, g, passes through the shank f, immediately below the wedge-shaped block G. A screw, H, passes through a hole in the bracket D and 50 screws into the back of the block G. It will thus be seen that by simply adjusting the block G by means of the screw H the bearing-box e may be raised or lowered in its jaws d, and through the said adjustment the door 55 A may be made perfectly level.

Instead of the roller B a bent plate, I, as shown in Fig. 3, may be used, and instead of the pair of rollers E a half-round cross-bar, J, as shown in Fig. 4, may be substituted. 65

What I claim as my invention is—

The bracket D, having jaws d, combined with the bearing e, held in said jaws, and provided with a vertical shank, the pin g in said shank, the wedge-shaped block G on said 70 shank and resting on said pin, and the adjusting-screw H, engaging said block, all arranged and operating substantially as shown and described.

Toronto, July 25, 1888.

REUBEN CLARKE.

In presence of—

CHARLES C. BALDWIN,
CHAS. H. RICHES.
